UNITED STATES PATENT OFFICE.

HOWARD R. SARGENT, OF SCHENECTADY, NEW YORK, ASSIGNOR TO GENERAL ELECTRIC COMPANY, A CORPORATION OF NEW YORK.

DIAL-PLATE FOR SWITCHES.

No. 863,808.

Specification of Letters Patent.

Patented Aug. 20, 1907.

Application filed August 24, 1905. Serial No. 275,572.

To all whom it may concern:

Be it known that I, HOWARD R. SARGENT, a citizen of the United States, residing at Schenectady, county of Schenectady, State of New York, have invented certain new and useful Improvements in Dial-Plates for Switches, of which the following is a specification.

This invention relates to rotary electric switches, and its object is to improve the mode of mounting the dial which indicates whether the switch is open or closed. 10 In this class of devices the dial usually bears the words "On" "Off", or the like, and the casing or cover which incloses the working parts of the switch has a suitable opening through which the proper word is visible to indicate the condition of the circuit at each position of the 15 switch.

My invention aims to provide a simple and inexpensive mode of mounting the dial, by supporting it upon extensions of the rotatable switch blade, whereby the dial is supported at its edges and therefore is not 20 liable to sag out of place. I provide, furthermore, an insulating plate underneath the metal dial so that the dial cannot come in contact with the stationary switch-contacts, and consequently it can be placed quite close to them: thus making a more compact structure.

25 In the accompanying drawing, Figure 1 is a plan view, with the cover half cut away; Fig. 2 is a side elevation, half in section; and Fig. 3 is a detail section on the line 3—3, Fig. 1, and on an enlarged scale.

The switch illustrated is of the ordinary type of rotary snap switch for controlling domestic lighting circuits and the like. It has an insulating base 1 carrying stationary contacts 2 and supporting a central spindle 3 carrying the independently-movable contact 4. In the drawing, only one stationary contact is shown, and 30 only one end of the movable contact, but the portions under the cover 5 are the same as those that can be seen. The cover is preferably provided with an insulating lining 6.

The movable contact has upwardly extending portions 7 which rise above the stationary contacts and are formed into tenons 7'. Said portions 7 are preferably the upturned ends of the movable switch-contact. An annular plate 8 of insulating material, such as fiber, rests on the shoulders at the base of said tenons. Above 45 this plate is a dial-plate 9 of thin sheet material, preferably metal, similar in size and shape to the plate 8, and having printed, painted or stamped thereon the words "On" and "Off": The plate 9 is cut away around the

tenons 7' to receive small washers 10 upon which the upper ends of the tenons are headed down. The washers are smaller than the holes in the plate 9, so that they do not come in contact therewith. The plate 9 is thus completely insulated from the movable contact, and is prevented by the plate 8 from touching the stationary contacts. 50

The dial-plate is supported in a position immediately beneath the top of the cover 5 in which is cut an opening 11 through which one of the words on the dial-plate can be seen. When the switch is closed, as shown in the drawing, the word "On" is visible, and when the movable switch-contact is rotated, the words "Off" and "On" appear alternately, as the switch opens and closes. Since the dial-plate is mounted on the movable contact, it partakes of the snap movements thereof, so 55 that the change from one word to the other occurs suddenly. 60

What I claim as new, and desire to secure by Letters Patent of the United States, is,—

1. In a rotary switch, the combination with the rotatable spindle, of a switch-contact having upwardly-extending portions, and a dial-plate supported on said portions. 70

2. In a rotary switch, the combination with the rotatable spindle, of a switch-contact having upturned ends, and a dial-plate supported on said ends. 75

3. In a rotary switch, the combination with the rotatable spindle, of a switch contact having upturned ends, and a dial-plate mounted thereon and insulated therefrom. 80

4. In a rotary switch, the combination with the rotatable spindle, of a switch-contact having upturned portions, an annular plate of insulating material mounted thereon, and a dial-plate supported on said insulating plate. 85

5. In a rotary switch, the combination with the rotatable spindle, of a switch-contact having upturned portions provided with tenons, an annular plate of insulating material mounted thereon, and a dial-plate supported on said insulating plate and cut away around said tenons. 90

6. In a rotary switch, the combination with the rotatable spindle, of a switch-contact having upturned ends provided with tenons, an annular plate of insulating material mounted thereon, a dial-plate supported on said insulating plate and having holes surrounding said tenons, and washers located in said holes out of contact with said dial-plate, said tenons being headed down on said washers. 95

In witness whereof I have hereunto set my hand this 23rd day of August, 1905.

HOWARD R. SARGENT.
